WASHING MACHINE

Edwin Cowles, Cleveland, Ohio, assignor to The Cowles Company, Princeton, N. J., a corporation of New Jersey

Application April 23, 1934, Serial No. 721,947

15 Claims. (Cl. 141—12)

This invention relates to washing machines, and has for its object to provide a machine suitable for washing soluble or insoluble substances from various materials. The material washed 5 may be granular or in the form of a powder, fibrous material such as paper pulp, or fabrics. The substances removed from the material being washed may be foreign matter carried off in suspension in the washing liquid or material 10 soluble in the washing liquid or both.

An important object of the present invention is to provide a washing machine in which the washing is carried out continuously in a plurality of stages, the washing liquid being carried 15 continuously through the various stages on the countercurrent principle, the fresh washing liquid being preferably brought into contact with the material in the final washing stage and being progressively carried from stage to stage so that 20 at each successive stage the washing liquid containing less of the substances extracted from the material being treated is brought into contact with the material containing less of the substances to be removed by the washing liquid.

25 It is to be understood that in some instances the countercurrent principle need not be extended to all of the washing stages, the use of the countercurrent principle in whole or in part being dependent upon the conditions inherent in the 30 particular washing operation to which the invention is applied. Also, the number of washing stages will vary with different materials.

With the above and other objects in view, the invention may be said to comprise the machine 35 as illustrated in the accompanying drawings, hereinafter described and particularly set forth in the appended claims, together with such variations and modifications thereof as will be apparent to one skilled in the art to which the invention 40 appertains.

Reference should be had to the accompanying drawings forming a part of this specification, in which

45 Figure 1 is a side elevation of a washing machine embodying the invention;

Fig. 2 is an end elevation looking toward the end from which the material being washed is discharged;

50 Fig. 3 is a section taken on the line indicated at 3—3 in Fig. 1;

Fig. 4 is a section taken on the line indicated at 4—4 in Fig. 1;

55 Fig. 5 is a section taken on the line indicated at 5—5 in Fig. 1;

Fig. 6 is a fragmentary, longitudinal section showing a modified construction; and

Fig. 7 is a vertical section through Fig. 6.

In the accompanying drawings the invention is illustrated as applied to a washing machine of 5 the rotating drum type into which washing liquid flows, and in which the powdered, granular or fibrous material is fed into one end of the drum and is gradually advanced to the discharge end 10 of the drum, where clean material is discharged. 10

As shown in the drawings by way of example, the machine comprises a rotatable drum 1 supported at its ends on tubular trunnions 2 and 3 which are rotatably supported by suitable means, such as rollers 4. At the inlet end of the drum 15 the trunnion 2 has an opening 5 at its outer end through which material may be introduced into the interior of the drum by any suitable means, such as a chute 6. The trunnion 3 has an opening 7 at its outer end through which material may 20 be discharged, and a discharge chute 8 may be provided to receive the material discharged from the drum. The bottom of the opening 5 is somewhat higher than the bottom of the opening 7, so that the liquid and material within the drum 25 will spill out through the opening 7 instead of the opening 5. If desired, the drum may be slightly inclined toward the discharge end. The drum 1 is rotated by suitable means, such as an electric motor 9, which may contain suitable reduction gearing, if desired, the motor being mounted on a supporting frame 10 and driving the drum through a suitable driving means, such as the belt 11.

The interior of the drum is divided into a series 35 of compartments by longitudinally spaced partitions 12 which are provided in the central portions thereof with openings 13 for the passage of material from compartment to compartment.

In each of the compartments there is a circumferentially continuous material-retaining screen 14 of perforated metal or wire suitable for retaining the particular material to be washed, and one or more layers of filtering material may be used therewith, if desired. The screens 14 in the 45 end compartments extend across the spaces between the end walls of the drum and the end partitions 12 and have their opposite edges attached to suitable supporting rings 15 secured to the inner faces of the end walls of the drum and 50 to the partition members. In the intermediate compartments the screens 14 extend across the compartments and are secured at their edges to supporting rings 15 attached to the partition members. The screens 14 are all disposed out- 55

wardly of the central openings 13 and are spaced inwardly of the peripheral wall of the drum, providing in each compartment an inner material retaining chamber, and an annular chamber exteriorly of the screen into which liquid may pass from the inner chamber through the screen or other filtering medium.

The machine of the present invention operates to subject the material to the washing action of the liquid in a series of stages and provides a construction whereby the counterflow principle to progressively subject material containing less impurities to washing liquid containing less impurities may be readily utilized. To this end, liquid moving means is provided for progressively transferring washing liquid from compartment to compartment in a direction opposite that in which the material being washed passes through the machine.

Extending between the partitions 12 and secured to said partitions and the shell of the drum are plates 16, 16a. As best shown in Fig. 5, the plates 16 extend substantially radially across the compartments exteriorly of the screen 14 and, together with the plates 16a, form scoops which will pick up liquid from the lower part of the annular space exteriorly of the screen during rotation of the drum and elevate the liquid.

Each partition 12 has openings 18 outwardly of the screens 14, each positioned adjacent the junction of the plates 16, 16a forming the scoops. In the intermediate compartments are pipes 19 which are secured at one end to blocks 17 carried by the rings 15 and are connected at the ends thereof toward the discharge end of the drum to the partition members 12 to receive liquid discharged through the openings 18.

Each pipe 19 extends across the compartment from the partition to which it is attached to the screen supporting ring at the opposite side thereof, where it is bent inwardly and attached to the ring to deliver liquid through an opening 20 in the ring to the interior of the material retaining chamber. Each of the openings 20 is provided at the inner end thereof with a gravity flap valve 21 which is closed by gravity and held closed during the passage of the scoop through the lower portion of its path of travel, but which will be opened by the pressure of the liquid in the pipes 19 after the scoops have been elevated above the level of the materials at the lower portion of the drum. Thus, during rotation of the drum, liquid is scooped up from the space surrounding the screen in each of the compartments between the compartment into which the material is fed at the inlet end of the drum and the discharge end of the drum, and is delivered into the material containing chamber of the next adjacent compartment toward the inlet end of the drum.

Hot or cold washing liquid, such as water, is introduced into the interior of the drum adjacent the discharge end of the drum by any suitable means, such as pipe 22. In each compartment the liquid passes through the filtering screen into the space between the screen and peripheral walls of the drum in the lower portion of the drum, and this liquid, during rotation of the drum, is picked up by the scoops and is constantly being transferred to the next adjacent compartments toward the inlet end of the drum.

At the periphery of the compartment at the inlet end of the drum the peripheral wall of the drum may be provided with liquid discharge openings 24, which deliver liquid to an arcuate chan-

nel collector trough 25 which delivers into a discharge pipe 26.

In the operation of the machine, the washing liquid passes through the screen 14, or other filtering medium, into the outer compartments 5 between the partitions 12, and during the rotation of the drum, a portion of the liquid is progressively transferred from compartment to compartment toward the inlet end of the drum.

The fibrous, granular, or other material is fed 10 into the inlet end of the drum through the chute 6 into the first washing compartment, where it is subjected to the first stage of the washing process. The agitation of the material caused by the rotation of the drum causes the material to pass 15 into the next compartment, and so on until it reaches the discharge end of the drum. In the first compartment into which the material to be washed is fed, the material is subjected to washing liquid which has passed successively through the other 20 compartments. In the second compartment from the inlet end the material is subjected to the second washing stage with liquid which has passed successively through other compartments 25 and which carries less impurities. When the material has passed through the successive compartments and the compartment at the discharge end of the drum, the greater portion of the impurities will have been removed and the relatively clean material will be subjected to the action 30 of clean liquid discharged into the final washing chamber by the inlet pipe 22. The material passes out through the discharge opening 7 onto the discharge chute 8. The material is thus subjected in the first stage to liquid which is most 35 heavily charged with impurities, and in successive stages is subjected to washing liquid which is progressively cleaner. In the final stage substantial clean material is subjected to substantially clean washing liquid.

The washing liquid, if water carrying dirt, may be discharged from the pipe 26 into a sewer, or if it contains valuable substances in solution it may be delivered to suitable recovery apparatus. In some instances it may be desirable to utilize 45 the liquid discharged through the delivery pipe 26 for an initial treatment of the material in a separate container prior to its introduction into the rotating drum. In the modified form in Figs. 6 and 7 is shown a compartment in which the partition member 12 carries a circumferential member 27 and an annular vertical flange 28 forming an annular trough extending a substantial distance across the compartment. Between the flange 28 and the next adjacent partition 50 member 12 is provided a screen or other filtering medium 14, as in the other compartments. With this construction the material passing through the opening 13 from the previous compartment will first enter a section where the washing liquid 55 is not permitted to drain freely, inasmuch as it is caught in the imperforate, annular trough and held in contact with the material which is being washed or treated for a period of time, before the material and liquid progress to the remainder 60 of the same compartment. The remaining portion of the compartment is provided with a screen or other filtering medium, through which the washing liquid may pass into the outer compartment, and there be transferred into the next 65 adjacent compartment by means of the scoops 16, 16a and pipes 19, as described above.

This longer period of treatment of the material being washed, with the washing liquid is 70 75

desirable for washing some materials, such, for example, as paper stock or fabrics.

It will be seen that while I have shown a washing machine with five washing compartments, any desired number of washing compartments may be used, and one or more of the washing compartments may be of the type in which a collector trough and discharge pipe are used, or may be of the type provided with scoops and pipes to automatically carry the water from one compartment into the previous compartment in the direction of flow of the material being washed through the machine.

It will also be seen that such compartments may be of the type shown in Fig. 1, or may be of the type containing a trough, such as shown in Figs. 6 and 7.

It will be apparent that the machine of the present invention is relatively simple, inexpensive and highly effective in operation, and that it is capable of washing impurities from materials treated very thoroughly and rapidly.

Furthermore, it is to be understood that the particular forms of apparatus shown and described, and the particular procedure set forth, are presented for purposes of explanation and illustration, and that various modifications of said apparatus and procedure can be made without departing from my invention, as defined in the appended claims.

What I claim is:

1. A washing machine comprising a rotatable drum, a transverse partition forming a dividing wall between compartments within the drum, a circumferentially continuous material-retaining member in each compartment spaced radially inwardly of the peripheral wall of the drum, means for introducing a washing liquid into one of the compartments, and means for transferring liquid from the space between said member and peripheral wall of the drum through said partition into the adjacent compartment.

2. A washing machine comprising a rotatable drum having transverse partitions dividing the interior thereof into a series of washing compartments, material retaining members in each compartment spaced radially inwardly of the peripheral wall of the drum, means for introducing washing liquid into one of the compartments, and means for simultaneously and progressively transferring liquid from the space between the material retaining members and the peripheral wall of the drum into the next adjacent compartment.

3. A washing machine comprising a rotatable drum having longitudinally spaced, transverse partitions dividing the drum into a series of compartments, said drum having an inlet for material to be washed at one end and an outlet for washed material at the other, said partitions having apertures in the central portions thereof for passage of a material being washed, circumferentially continuous material-retaining means in each compartment spaced inwardly from the peripheral wall of the drum and across the compartments outwardly of the said apertures, means for introducing a washing liquid into one of the compartments at the discharge end of the drum, and means for progressively transferring liquid from compartment to compartment toward the material inlet end of the drum.

4. A washing machine comprising a rotatable drum having longitudinally spaced transverse partitions dividing the drum into a series of compartments and having a material inlet at one end

and a material outlet at the other, said partitions having openings in the central portion thereof for passage of the material being washed from one compartment to another, circumferentially continuous material retaining means in each compartment spaced inwardly from the peripheral wall of the drum and across the compartments outwardly of said partition openings, said material retaining means being pervious to the washing liquid, scoops for picking up liquid escaping through the material retaining means in one compartment, and automatic means for transferring the liquid into the next adjacent compartment toward the material inlet of the drum.

5. A washing machine comprising a rotatable drum having longitudinally spaced, transverse partitions dividing the drum into a series of compartments, said drum having an inlet for material to be washed at one end and an outlet for washed material at the other, said partitions having apertures in the central portions thereof for passage of material, circumferentially continuous material-retaining screens in each compartment spaced inwardly from the peripheral wall of the drum and across the compartments outwardly of the said apertures, means for introducing a washing liquid into the compartment at the discharge end of the drum, means for delivering liquid from the space outside the screen of the compartment at the outlet end of the drum to the interior of the screen of the next compartments, and similar means for transferring liquid from compartment to compartment toward the inlet end of the drum.

6. A washing machine having a series of washing compartments through which material to be washed may be advanced, means for supplying a washing liquid to one of the final washing compartments, one of said washing compartments having means for retaining both liquid and material in the compartment for a portion of the travel of the material through the compartments and having a material retaining screen for retaining the material while permitting the washing liquid to pass therethrough for the rest of the travel through said compartment.

7. A washing machine comprising a rotatable drum, transverse partitions disposed in the drum dividing the interior thereof into a series of washing compartments, said partitions having openings to permit travel of the material being washed through said partitions, a circumferentially continuous filtering member disposed in said compartments and spaced radially inwardly of the peripheral wall of the drum, at least one of said compartments having an imperforate trough member to retain both the material to be washed and the washing liquid for a substantial portion of the travel of the material being washed across said compartment.

8. A washing machine comprising a rotatable drum, transverse partitions disposed in the drum dividing the interior thereof into a series of washing compartments, said partitions having openings to permit travel of the material being washed through said partitions, a circumferentially continuous filtering member disposed in said compartments and spaced radially inwardly of the peripheral wall of the drum, at least one of said compartments having an imperforate trough member to retain both the material to be washed and the washing liquid for a substantial portion of the travel of the material being washed across said compartment, the remainder of said com-

partment having filtering means to permit the washing liquid to pass therethrough, and means for automatically and progressively transferring liquid collecting between the filtering member and the peripheral wall of the drum into the next adjacent compartment toward the material inlet of the drum.

9. A washing machine comprising a rotatable drum having longitudinally spaced, transverse partitions dividing the drum into a series of compartments, circumferentially continuous filtering means in each compartment spaced inwardly from the peripheral wall of the drum, said partitions having openings therein inwardly of the filtering means, means disposed between the filtering means and the peripheral wall of the drum for picking up from the bottom portion of the drum, liquid which has passed through the filtering material, and transfer means operable when the pressure of the liquid outside the filtering medium is greater than the pressure of the material being washed to automatically transfer the liquid into the next adjacent washing compartment inwardly of the filtering medium.

10. A washing machine comprising a rotatable drum having a material inlet at one end and a material outlet at the other end, and having longitudinally spaced, transverse partitions dividing the drum into a series of compartments, circumferentially continuous filtering means in each compartment spaced inwardly from the peripheral wall of the drum, said partitions having openings therein inwardly of the filtering means, means disposed in a plurality of compartments between the filtering means and the peripheral wall of the drum for picking up from the bottom portion of the drum, liquid which has passed through the filtering material, and transfer means operable when the pressure of the liquid outside the filtering medium is greater than the pressure of the material being washed to automatically transfer the liquid from said compartments into the next adjacent compartments toward the material inlet of the machine and inwardly of the filtering medium.

11. A washing machine comprising a rotatable drum having transverse partitions dividing the interior thereof into a plurality of washing compartments, circumferential filtering means disposed in each compartment inwardly of the periphery of the drum, scoops disposed in one compartment between the filtering means and the periphery of the drum, conduits disposed in the next adjacent compartment outwardly of said filtering means, said conduits having one end opening through the partition into said scoops, valves disposed at the opposite end of said conduits and leading into the inner portion of said adjacent compartments, said valves being mounted to open as the rotation of the drum carries upwardly the liquid in said scoops, whereby the liquid collected in the scoop of one compartment is automatically transferred into the inner portion of said adjacent compartment, and means for supplying liquid to said washing machine.

12. A washing machine comprising a rotatable drum having a material inlet and a material outlet, and having transverse partitions dividing the

interior thereof into a plurality of washing compartments, said partitions having openings in the inner portion thereof to permit the material to pass from one compartment into the next, circumferential filtering means disposed in each compartment inwardly of the periphery of the drum, scoops disposed in one compartment between the filtering means and the periphery of the drum, conduits disposed in the next adjacent compartment toward the material inlet of the machine and outwardly of said filtering means, said conduits having one end opening through the partition into said scoops, valves disposed at the opposite end of said conduits and leading into the inner portion of said adjacent compartment, said valves being mounted to open as the rotation of the drum carries upwardly the liquid in said scoops, whereby the liquid collected in the scoop of one compartment is automatically transferred into the inner portion of said adjacent compartment toward the material inlet of the machine, and means for supplying liquid to one of the compartments adjacent the material outlet.

13. A washing machine comprising a rotatable drum having a material inlet and a material outlet at opposite ends thereof and a series of separate longitudinally spaced transverse partitions forming a series of separate washing compartments within the drum between the inlet and outlet thereof, said partitions having openings inwardly of the periphery of the drum for passage of the material being washed from compartment to compartment, and means for introducing a washing liquid into one of the compartments adjacent the material outlet and for transferring washing liquid from compartment to compartment in a direction opposite that of the flow of material being washed.

14. A washing machine comprising a rotatable drum having a material inlet and a material outlet at opposite ends thereof and a series of separate longitudinally spaced transverse partitions forming a series of separate washing compartments within the drum between the inlet and outlet thereof, said partitions having openings inwardly of the periphery of the drum for passage of the material being washed from compartment to compartment, means for introducing a washing liquid into a compartment adjacent the material outlet, and means for collecting liquid from the last mentioned compartment, elevating the liquid and discharging the same into a compartment nearer the material inlet.

15. A washing machine comprising a rotatable drum having a material inlet and a material outlet at opposite ends thereof and a series of separate longitudinally spaced transverse partitions forming a series of separate washing compartments within the drum between the inlet and outlet thereof, said partitions having openings inwardly of the periphery of the drum for passage of the material being washed from compartment to compartment, means for introducing a washing liquid into the drum adjacent the material outlet, means within the drum for collecting liquid from each of a plurality of compartments and transferring the liquid collected from each compartment into other compartments nearer the material inlet.
